(57) **CLAIM**

The ornamental design for a hockey table with slanted rails, as shown and described.

DESCRIPTION

FIG. 1 is a perspective view of the billards table and slanted rails.

FIG. 2 is a top elevation view thereof.

FIG. 3 is a side elevational view thereof.

FIG. 4 is an end-on view thereof.

FIG. 5 is a fragmentary view of a portion of the table and rail; and,

FIG. 6 is a cross-sectional view of the slant rail.

The broken lines are for illustrative purpose only and form no part of the claimed design.
